SEALED PACKAGE

Edgar Scofield, New York, N. Y., assignor to
Anchor Cap & Closure Corporation, Long
Island City, N. Y., a corporation of New York

Application November 26, 1928, Serial No. 321,897

12 Claims. (Cl. 215—40)

The present invention relates to the sealing art and more particularly to a sealed package and the parts thereof.

Many products are very difficult to keep and have to be hermetically sealed to keep out germs; some of them are sealed under a partial vacuum in order to secure best results. In the shipment of the containers after the sealing operation, and in handling them, they constantly bump against each other, against the partitions in the cases and against other extraneous objects. Frequently this impairs the seal and breaks the vacuum.

Certain seals at the present time have what may be called a cover cap, which is generally a small disc fitting over the upper end of the container under the regular closure. The cover cap may be used for covering the container during consumption after the regular cap is removed. In some cases, these cover caps are secured in position by screw bands, in other cases by bands fitting over the outer edge of the cap and secured to the container through the intermediation of a gasket. The present practice is to ship the cover caps separately and to apply them separately from the regular closures. In some cases, the cover caps and closure caps are shown assembled by means of notches and projections registering for the assembling operation. The assembly of such articles requires considerable manual work to position the cover cap with respect to the closure cap in order to assemble them.

The present invention aims to eliminate the objections, to improve structures such as those described above and to provide a cover cap and closure cap which co-operate with each other to form a better seal than those heretofore, and which will resist the accidental jars and knocks without impairment of the seal. The present invention also contemplates the provisions of a cover cap which may be readily assembled with closure caps for shipping, sealing and other desirable operations.

An object of the invention is to provide a secure hermetic seal adapted to maintain a vacuum and adapted also to resist jars and accidental knocks without impairment of the seal or of the vacuum.

Another object of the invention is to provide a double seal by co-operation between a closure cap and a cover cap through the intermediation of a single gasket.

Another object of the invention is to provide a cover cap adapted to be assembled with a closure cap and shipped and applied in assembled

state, and adapted also to be sealed to the container to prevent contamination of the exterior thereof.

Another object of the invention is to provide a cover cap adapted to fit into a closure cap and to be held therein through the intermediation of the gasket in the closure cap.

Other and further objects of the invention will be obvious upon an understanding of the illustrated embodiment about to be described or will be indicated in the appended claims, and various advantages not referred to herein will occur to one skilled in the art upon employment of the invention in practice.

A preferred embodiment of the invention has been chosen for purposes of illustration and description and is shown in the accompanying drawing, wherein:

Fig. 1 is a sectional view, with parts in elevation, of a cover cap assembled with a closure cap on a container prior to the sealing operation;

Fig. 2 is a sectional view, with parts in elevation, illustrating the structure shown in Fig. 1 sealed to a container;

Fig. 3 is a fragmentary sectional view of a different form of construction; and

Fig. 4 is a fragmentary sectional view illustrating another form of construction.

Referring to the drawing, there is shown in Figs. 1 and 2 a closure cap 1 having a cover portion 2 and a depending skirt 4 with a bead 5 therein, the lower edge 6 of the cap being turned inwardly to form the lower side of the bead. A cover cap 7 nests in the closure cap with the cover portion 8 adjacent the cover portion of the closure cap and with the depending flange 9 adjacent the skirt of the closure cap. The lower edge of the cover cap is turned outwardly to fit under the upper side of the bead 5, the portion 9 of the cover cap being of sufficient length to retain the outer edge 10 of the cover cap in the upper part of the bead. The gasket 11 is assembled into the bead 5 and held therein by means of the flange 6 on the closure cap. The upper side of the gasket rests against the outwardly flared edge of the cover cap to hold the cover cap in position.

Since the gaskets preferably are made of vulcanized rubber, their resiliency is such that the cover cap is held in position and may be shipped, handled and sealed without becoming disassembled. In fact, the inclination of the side of the skirt may be sufficient to permit the caps to stack one upon another, the lower edge 6 raising above the bead of an adjoining cap. When placed in a sealing machine the stacked caps may be fed

automatically, thereby minimizing any tendency for the gaskets to drop out.

The container 12 shown in Fig. 2 is preferably a glass tumbler having a cylindrical surface 14 adjacent its upper edge for co-operating with the gasket to form a secure seal. While the seal may be made in various ways, preferably the bead is compressed into the shape shown in Fig. 2, which will press the gasket firmly against the container and firmly against the outwardly flared edge 10 of the cover cap. The deformation of the bead forming the seal and the mechanism for constricting the bead may be similar to that described in my Patent No. 1,611,955 dated December 28, 1926.

In Fig. 3 another form of construction is shown wherein the container has a cylindrical surface 15 in line with the gasket and also an annular surface 16 having a smaller diameter separated from the surface 15 by a shoulder 17. The outer flare at the lower edge of the cover cap is omitted, permitting the flange 18 of the cover cap to be substantially cylindrical or flared outward slightly to facilitate application.

The cover cap fits snugly over the smaller surface 16 of the container and substantially abuts the shoulder 17. The gasket is squeezed against the container by deformation of the bead 5, the upper part of the gasket engaging the flange of the cover cap. Part of the gasket is squeezed during the sealing operation into the small space between the lower edge of the cover cap and the shoulder 17. In this way, a very secure seal is formed because the wide zone of engagement between the gasket and the cylindrical surface 15 provides a secure seal. In addition, the upper part of the gasket, in fitting between the lower edge of the cover cap and the shoulder 17, seals the latter to the container. The closure cap and the cover cap co-operate to form a double seal through the intermediation of a single gasket.

In Fig. 4 the upper edge of the surface 15 on the container ends in an outwardly extending shoulder 19 which gives greater holding power to the seal between the gasket 11 and the closure cap. The cover portion of the cover cap conforms approximately to the upper edge of the container, the lower part of the cover being pressed into the container as shown at 20.

It will be seen that a construction has been provided in which a double seal is formed through the intermediation of a single gasket. The seal is better able to withstand the rough usage to which it may be subjected without impairment of the hermetic seal or impairment of the partial vacuum formed in the container. The parts are simple in construction, may be shipped, assembled and sealed with a minimum of trouble and cost. The cover cap not only provides a more effective seal, but it furnishes a convenient cover for the contents of the package during consumption, it being necessary with most types of closures to mar or substantially destroy them in removing. It will be understood that the cover cap herein is not marred or spoiled during the opening of the seal. Further, the cover cap being sealed to the container, there is no chance of the contents seeping around the edge of the cap and soiling the exterior thereof.

As various changes may be made in the form, construction and arrangement of the parts in the above embodiment without departing from the spirit of the invention, it is to be understood that all matter herein is to be interpreted as illustrative and not in a limiting sense.

Having thus described my invention, I claim:

1. A sealed package comprising a container, a closure cap having a bead in the skirt thereof, a gasket in said bead, and a cover cap having its lower edge extending downwardly over the container and outwardly over said gasket into said bead. 80

2. A sealed package comprising a container, a closure cap having a bead in the skirt thereof, a gasket in said bead, and a cover cap provided with a skirt portion having its lower edge extending outwardly over said gasket into said bead, said bead being compressed to squeeze said gasket against said container to form a seal with said closure cap and also with said cover cap. 85

3. A sealed package comprising a container, a cover cap provided with a depending skirt, a closure cap fitting over said cover cap and completely enclosing it, an annular gasket in the skirt of said closure cap fitting against the lower edge of the skirt of the cover cap, said skirt being reformed to force the entire inner periphery of the gasket against the container to form a seal between the skirt of said cover cap and the container and between said closure cap and the container, thereby to provide a double seal on the container through the intermediation of a single gasket. 90

4. As an article of manufacture, a closure cap comprising a cover portion, a depending skirt 105 having a bead therein, a gasket in said bead, and a cover cap nested in said closure cap, said cover cap being provided with a skirt portion flared outwardly at the lower edge thereof, and extending between said gasket and the upper side of 110 said bead.

5. As an article of manufacture, a closure cap comprising a cover portion, a depending skirt having a bead therein, the lower edge of the closure cap being turned inwardly to form the 115 lower side of said bead, a cover cap nested in said closure cap, the outer periphery of said cover cap extending into said bead and being smaller in diameter than the internal diameter of the lower edge of the closure cap, and a gasket in 120 said bead abutting against the lower periphery of said cover cap for providing a seal for both said cover cap and said closure cap to provide a double seal on a container.

6. As an article of manufacture, a closure cap 125 comprising a cover portion, a depending skirt having a bead therein, the lower edge of the closure cap being turned inwardly to form the lower side of said bead, a cover cap nested in 130 said closure cap, the outer periphery of said cover cap extending into said bead and being smaller in diameter than the internal diameter of the lower edge of the closure cap, and a gasket in 135 said bead adapted to hold said cover cap in position and to seal the container by means of the cover cap.

7. A sealed package comprising a container having a substantially cylindrical surface adjacent the mouth thereof ending in a shoulder, a cover cap fitting over said cylindrical surface and 140 extending substantially to said shoulder, a closure cap extending over the cover cap, and a gasket in said closure cap adjacent to said shoulder and to the lower edge of the cover cap, said gasket being pressed into engagement with the lower 145 edge of the cover cap and into engagement with the container to form a double seal on the container.

8. A sealed package comprising a container having a smooth annular surface adjacent the 150

- upper end, and a second annular surface below said smooth surface, said second surface having a larger diameter than said upper smooth surface, a cover cap secured to said smooth surface, a closure cap having a bead in the skirt thereof, and a gasket in said bead, said bead being compressed so that the gasket contacts the lower edge of the cover cap and hermetically seals said closure cap to said second surface having a larger diameter. 86
- 5 9. A sealed package comprising a container, a cover cap extending over and telescoping about the end of said container, a closure cap extending completely over and completely enclosing the cover cap, and a gasket in said closure cap, the lower edge of said cover cap extending below the upper edge of said gasket whereby said gasket is adapted to seal both the cover cap and the closure cap upon the container, thus forming a double seal on the container with a single gasket. 85
- 10 10. A sealed package comprising a container having a substantially cylindrical surface adjacent the mouth thereof, a cover cap fitting over said cylindrical surface, a closure cap extending over the cover cap and adapted to form a hermetic seal on the container independently of the cover cap, and a gasket in said closure cap, said gasket being pressed into engagement with the lower edge of the cover cap to hermetically seal 90
- 15 30 35 40 45 50 55 60 65 70 75
- said cover cap and said closure cap on the container. 11. As an article of manufacture, a closure cap comprising a cover portion, a depending skirt having a bead formed in the lower portion thereof, a gasket in said bead, and a cover cap nested in said closure cap, said cover cap having a depending skirt substantially shorter than the skirt of said closure cap and flared outwardly at its lower edge whereby the gasket in the bead is adapted to engage and support the lower edge of the skirt of the cover cap to lock said two caps together and to prevent accidental separation thereof. 95
- 20 25 30 35 40 45 50 55 60 65 70 75
12. In a two-piece closure for sealing containers and the like, a closure cap constructed of sheet metal adapted to be reformed, but of sufficient thickness to prevent tearing thereof, said closure cap comprising a cover portion, a depending skirt, a bead formed in the lower portion of the skirt and a gasket disposed in the bead, and a cover cap constructed of like material as said closure cap nested in said closure cap, the gasket in the bead engaging the lower edge of said cover cap to hold it in position and to prevent said two caps from being separated after once assembled. 100
